ELECTRIC TILTING FURNACE

Lloyd L. Babcock, Compton, and John D. Spalding, Los Angeles, Calif., assignors to The National Supply Company, Pittsburgh, Pa., a corporation of Pennsylvania

Application May 22, 1948, Serial No. 28,556

7 Claims. (Cl. 13—10)

1

This invention relates to electric furnaces and is particularly directed to arc-type furnaces employed in the production of ferrous metals and alloys.

The charging of materials into a furnace shell for melting may be accomplished through a charging opening in the shell, but is preferably accomplished by exposing the entire upper portion of the shell so that charging may take place through the top. Top charging electric melting furnaces have commonly employed a swing-aside roof, or as an alternative a shell which may be moved out from under the roof when desired, and in this way the charging operation may be effected in a minimum of time. The principal invention relates to the latter type of furnace in which the furnace shell may be rolled out from under the roof on rails provided for that purpose.

It is an important object of this invention to provide an electric melting furnace having an electrode support and electrical equipment at one side and means for moving the furnace shell out from under the furnace roof in a direction away from the electrode support, the entire furnace including the roof and shell being tiltable about an axis parallel to the direction of movement of the shell in order that the entire furnace may be tilted in one direction toward a pouring pit and tilted in the opposite direction toward a slagging off pit.

Another object is to provide an improved roof supporting structure, together with novel means for lifting the roof sufficiently to enable the shell to be moved laterally from under the roof.

Other objects and advantages will appear hereinafter.

In the drawings:

Figure 1 is a side elevation showing a preferred embodiment of this invention.

Figure 2 is a front elevation thereof showing the pouring spout.

Figure 3 is a top plan view.

Figure 4 is a sectional detail taken substantially on the lines 4—4 as shown in Figure 2.

Figure 5 is a sectional perspective view illustrating details of the structure for elevating the furnace roof.

Figure 6 is a sectional elevation taken substantially on the lines 6—6 as shown in Figure 5.

Figure 7 is a partial sectional view on an enlarged scale taken substantially on the lines 7—7 as shown in Figure 6.

Figure 8 is a sectional plan view partly broken away taken substantially on the lines 8—8 as shown in Figure 1.

2

Referring to the drawings, the furnace generally designated 10 includes a shell 11 and a roof 12. A pair of spaced main supporting beams 13 extend across a central pit 14 and are supported adjacent the ends on the walls 15 forming sides of the pit 14. Each of the main support beams 13 carries a rack 16 on its upper surface. A pair of spaced gear segments 17 connected by cross-beams 18 and 18a provide a rocking support base 19 for the furnace 10. Transverse beams 20 secured to the support base 19 are pivotally connected to the upper end of a pair of links 21. The lower ends of the links 21 are pivotally mounted at 22 to a gear wheel 23 rotatably supported on the base 24 positioned within the central pit 14. Pinions 25 mounted on drive shaft 26 are adapted to be driven from a source of power 27. From this description it will be understood that rotation of the drive shaft 26 serves to turn the pinions 25 and gear wheels 23 to cause the links 21 to tilt the support base 19 in either direction from the vertical.

A pouring spout 28 is secured to the furnace shell 11 at one side and positioned over a pouring pit 29. A door 30 is mounted on the furnace shell 11 diametrically opposite the pouring spout 28 and positioned to close the slag-off opening 31. A short lip or spout 32 is mounted below the opening 31 in position to pour into a slag-off pit 33.

The beams 18 on the tiltable support base 19 support parallel rails 34 which extend outwardly away from the electrode supporting structure 35. These rails 34 carried by the tiltable support base 19 are adapted to be aligned with stationary rails 36 which extend away from the furnace to a location where the shell 11 is to be charged with material to be melted. The shell is provided with a plurality of supporting wheels 37 adapted to roll on the rails 34 and on the rail extensions 36.

Power means is provided on the tiltable support base 19 for moving the frame shell laterally on the rails 34, and as shown in the drawings 45 this power means includes a pair of sprockets 38 mounted on a drive shaft 39 adapted to be driven from a motor and reduction unit 40 carried on the tiltable support base 19. Chains 41 having their opposed ends fixed to cover guards 42 extend under the shell 11 parallel to the rails 34 and are adapted to be engaged by the sprockets 38. Accordingly, rotation of the motor and reduction unit 40 turns the sprockets 38 and causes the shell 11 to roll along the rails 34 and outward onto the rail extensions 36. The parts are proportioned so that the sprockets

38 maintain contact with the chains 41 while the furnace shell 11 rolls completely out from under the roof generally designated 12. After the shell 11 has been charged through the open top with material to be melted, the motor and reduction gear 40 is again energized to cause the shell 11 to roll back into position under the roof 12. A skirt or guard 72 may be provided on the forward portion of the shell 11 to cover the sprockets 38, drive shaft 39 and associated mechanism when the shell 11 is in position under the roof 12.

As shown in Figure 5, laterally spaced upright beam sections 43 are secured to the tiltable support base 19 at their lower ends and are connected by rigid cross-members 44. These upright beams 43 are formed as box sections to enclose supporting and elevating mechanism for the roof 12. A power shaft 45 is rotatably supported on bearing assemblies 46 mounted on the upright beam sections 43 and is provided with an extending portion 47 at one end adapted to be driven from a suitable source of power (not shown). Formed integrally on the shaft 45 and positioned within the enclosures 48 provided by the upright beam sections 43 is a pair of eccentrics 49. An eccentric strap 50 encircles each of the eccentrics 49 and is pivotally connected at 51 to the lower end of a post 52 mounted within the enclosures 48. Each of the upright beam sections 43 is provided with a lower roller 53 and an upper roller 54 adapted to contact opposite sides of the posts 52. A pair of forwardly extending roof supporting beams 55 is carried on the upper ends of the posts 52. The beams are connected at their extending ends by transverse beam 56. Gussets 57 may be provided to supply stiffness to the connection between the horizontal beams 55 and the vertical posts 52.

The beams 55, 56 and posts 52 comprise a supporting and lifting yoke for the roof ring 58. The roof ring 58 is suspended from the parallel support beams 55 by means of connecting links 59. Refractory material 60 carried by the ring 58 forms the arched roof of the furnace. In its normal operative position the roof ring 58 rests on the upper flange 61 of the shell 11 so that the refractory linings 60 and 62 of the roof and shell provide a closed space within the furnace. When it is desired to lift the roof 12 in order to roll the shell laterally out from under the roof into charging position, the shaft 45 is turned to cause the eccentrics 49 to lift the posts 52 and horizontal beams 55. This action lifts the ring 58 clear of the flange 61 and permits the shell to be laterally moved. It will be observed in Figure 6 that the weight of the beams 55 and roof 12 is carried on the eccentrics 49, and the posts are guided by means of the upper and lower rollers 54 and 53 respectively on the upright beam sections 43. This construction allows the roof 12 to be raised vertically with a minimum of shock and vibration in order that the refractory brick 60 may not be displaced or damaged.

The electrode supporting structure 35 includes a pair of end columns 63 extending upwardly from the upright beam sections 43, together with a plurality of channel sections 64 also mounted in upright position and connected to the upright beam sections 43, transverse stiffener 44 and shelf 71. A cap structure 65 connects the upper ends of the column 63 and channel 64. The channels 64 are arranged in pairs having their

end flanges inwardly directed to provide guide ways for carriers 66 adapted to travel vertically between the pairs of channels 64.

As shown in Figure 8, the carriers 66 are provided with rollers 67 adapted to engage the flanges 68 of the channels 64 for guiding the carriers 66. The rollers 67 may be mounted on the carrier 66 at vertically spaced locations as shown in Figure 1. A suitable mechanism (not shown) is provided for raising and lowering the carrier 66 relative to the channel 64. Such mechanism is well known in the art and serves to raise and lower the electrode supports in order to feed and retract the three carbon electrodes 69 into the furnace through the roof 12. Each of the carriers 66 supports a clamp 70 which engages one of the carbon electrodes 69. The electrical leads for conducting current to the electrode holders 70 are omitted in the drawing for clarity of illustration, but it is to be understood that they connect to suitable transformer equipment located back of the furnace 10 on the opposite side of the electrode supports 35 from the roof 12. In other words, the shell 11 rolls out from under the roof 12 in a direction away from the transformer equipment (not shown). From the above description it will be understood that when the furnace 10 is tilted toward the pouring pit 29 or slag-off pit 33 the electrode supporting structure 35, electrode 69, and roof 12 tilt as a unit with the shell 11 and tilttable support base 19.

In operation the roof 12 is elevated by rotating the eccentric shaft 45, and the shell 11 is rolled out under the rail extensions 35 by means of the drive sprockets 38. The shell is then charged through the open top thereof with the material to be melted, and is then rolled back into position under the roof 12. The electrodes 69 are lowered through the roof 12 and the roof 12 is then lowered by rotation of the eccentric shaft 45 to allow the roof to rest on the upper end of the shell 11. Electrical energy is then supplied to the carbon electrodes 69 and the furnace operates in the conventional manner to melt the material within the shell by the action of the electric arc.

During the melting or refining of ferrous metals or alloys it is necessary for metallurgical reasons to withdraw from the furnace the slag which forms and floats on the surface of the molten metal within the shell. The operation of removing this slag is known in the art as "slagging-off" and is accomplished through the opening 31 upon movement of the door 30 to open position. The furnace 10 is then tilted by rotation of the gear wheel 23 so that the pouring spout 28 is elevated and the slag-off lip 32 is lowered. A rabble bar (not shown) is then inserted through the door 31 and manipulated by an operator to withdraw the floating slag from the pool of molten metal, and this slag falls into a suitable container positioned within the slag-off pit 33. When the slag-off operation is complete the rabble bar is withdrawn, the door 30 closed, and the furnace 10 returned to its normal upright position.

When the heat is ready to pour a ladle is positioned within the pouring pit 29 and the gear wheel 23 is rotated to tilt the furnace in a direction to lower the pouring spout 28, and the pouring operation is accomplished in the customary fashion. When the heat has been poured the gear wheel 23 is rotated to bring the furnace 10 back to its normal upright position, and the carriers 66 are raised (not shown) to

withdraw the electrode 89 upwardly out of the shell 11. The roof 12 is then elevated and the shell 11 rolled out on the rails 34 and 36 for recharging.

Having fully described our invention, it is to be understood that we do not wish to be limited to the details herein set forth, but our invention is of the full scope of the appended claims.

We claim:

1. In an electric melting furnace, the combination of: a tiltable support base; parallel horizontal rails on said support base positioned at right angles to the direction of tilting movement of the support base; relatively fixed rail extensions aligned with said rails when the support base is in horizontal position; a furnace shell provided with wheels resting on said rails and provided with a pouring spout and a slag-off opening at diametrically opposite locations; a furnace roof positioned above the shell and cooperable therewith to define a furnace enclosure; means for supporting the roof independently of the shell including upright support structure fixed on said base at one end of the rails and located adjacent the periphery of the shell intermediate the positions of the pouring spout and slag-off opening; and cooperating means on the shell and tiltable support base whereby the shell may be moved laterally out from under the furnace roof onto the rail extensions in a direction at right angles to the pouring spout.

2. In an electric melting furnace, the combination of: a tiltable support base mounted between a pouring pit and a slag-off pit; parallel horizontal rails on said support base positioned at right angles to the direction of tilting movement of the support base; relatively fixed rail extensions aligned with said rails when the support base is in horizontal position; a furnace shell provided with wheels resting on said rails and provided with a pouring spout adjacent the pouring pit and a slag-off opening adjacent the slag-off pit; a furnace roof positioned above the shell and cooperable therewith to define a furnace enclosure; means for supporting the roof independently of the shell including upright support structure fixed on said base at one end of the rails and located adjacent the periphery of the shell intermediate the positions of the pouring spout and slag-off opening; lifting means associated with said support structure for raising the furnace roof upwardly away from said shell; and cooperating means on the shell and tiltable support base whereby the shell may be moved horizontally out from under the furnace roof onto the rail extensions in a direction at right angles to the pouring spout without passing over either of said pits.

3. In an electric melting furnace, the combination of: a tiltable support base; parallel rails on said support base positioned at right angles to the direction of tilting movement of the support base; a furnace shell having supporting wheels thereon resting on said rails, said shell being provided with a pouring spout and a slag-off opening at diametrically opposite locations on opposite sides of said parallel rails; a furnace roof positioned above the shell and cooperating therewith to define a furnace enclosure; means for supporting the roof independently of the shell including upright support structure fixed on said base at one end of the rails and located adjacent the periphery of the shell intermediate the positions of the pouring spout and slag-off opening; and means for rolling the shell along the rails

laterally out from under the furnace roof in a direction away from the roof support structure.

4. In an electric melting furnace, the combination of: a tiltable support base mounted between a pouring pit and a slag-off pit; parallel horizontal rails on said support base positioned at right angles to the direction of tilting movement of the support base; relatively fixed rail extensions aligned with said rails when the support base is in horizontal position; a furnace shell provided with wheels resting on said rails and provided with a pouring spout adjacent the pouring pit and a slag-off opening adjacent the slag-off pit; a furnace roof positioned above the shell and cooperable therewith to define a furnace enclosure; means for supporting the roof independently of the shell including upright support structure fixed on said base at one end of the rails and located adjacent the periphery of the shell intermediate the positions of the pouring spout and slag-off opening; means carried by the base for effecting relative vertical movement between the shell and the roof; and cooperating means on the shell and tiltable support base whereby the shell may be moved horizontally out from under the furnace roof onto the rail extensions in a direction at right angles to the pouring spout.

5. In an electric melting furnace, the combination of: a tiltable support base; a pair of parallel horizontal rails positioned on the base at right angles to the direction of tilting movement of the base; a furnace shell provided with support wheels resting on said rails; a pouring spout on the furnace shell at right angles to the direction of the rails; relatively fixed rail extensions aligned with the said rails when the support base is in horizontal position; and power means on the support base selectively operable to roll the shell on its supporting wheels along said rails and onto said rail extensions, said power means including a rotatable drive element positioned near the juncture of the rails and rail extensions and adapted to cooperate with a driven element mounted on the furnace shell.

6. In an electric melting furnace, the combination of: a tiltable support base; a pair of parallel horizontal rails positioned on the base at right angles to the direction of tilting movement of the support base; a furnace shell provided with support wheels resting on said rails; a pouring spout on the furnace shell at right angles to the direction of the rails; relatively fixed rail extensions aligned with the said rails when the support base is in horizontal position; a roof cooperable with the shell to form a furnace enclosure, support means on the base at one end of the rails for supporting the roof independently of the shell; and power means on the support base selectively operable to roll the shell on its supporting wheels along said rails away from the support means and onto said rail extensions, said power means including a rotatable drive element positioned near the juncture of the rails and rail extensions and adapted to cooperate with a driven element mounted on the furnace shell.

7. In an electric melting furnace, the combination of: a tiltable support base; parallel horizontal rails on said support base positioned at right angles to the direction of tilting movement of the support base; relatively fixed rail extensions aligned with said rails when the support base is in horizontal position; a furnace shell provided with wheels resting on the rails and provided with a pouring spout and a slag-off opening at diametrically opposite locations; means for

tilting the base in a direction toward either the pouring spout or slag-off opening; a furnace roof positioned above the shell and cooperable therewith to define a furnace enclosure; means on the tiltable base for supporting the roof independently of the shell; and cooperating means on the shell and tiltable support base whereby the shell may be moved laterally out from under the furnace roof onto the rail extensions in a direction at an angle to the pouring spout.
